(57) **CLAIM**

The ornamental design for a dispenser, as shown and described.

DESCRIPTION

FIG. 1 is a top, front, right perspective view of a dispenser showing our new design;

FIG. 2 is a front view thereof;

FIG. 3 is a left side view thereof, wherein the right side is a mirror image of FIG. 3;

FIG. 4 is a rear view thereof;

FIG. 5 is a top view thereof; and,

FIG. 6 is an enlarged and partial bottom, front perspective view thereof.

The broken lines showing the remainder of the dispenser are for environmental purposes only and form no part of the claimed design. The wavy broken lines in FIG. 6 are imaginary break lines and form no part of the claimed design.
